ENVELOPE STUFFING MACHINE

Horace C. Baker, Green Bay, Wis., assignor to
Patten Paper Company, Ltd., Appleton, Wis.

Application August 20, 1931, Serial No. 558,387

8 Claims. (Cl. 93—6)

The invention relates to an envelope filling machine, and more especially to an automatic envelope stuffing machine.

The primary object of the invention is the provision of a machine of this character, wherein envelopes can be successively in single order brought into position for receiving letter sheets and the latter stuffed thereinto without requiring the manual handling of said envelopes, and when these envelopes have been filled or stuffed the same will be stacked on delivery thereof.

Another object of the invention is the provision of a machine of this character, wherein the mechanism for the handling of the envelopes is novel in form and likewise the means for feeding the sheet paper thereinto is novel, so that the entire working of the machine is automatic and eliminates the manual handling of the envelopes for the stuffing or filling of the same.

A further object of the invention is the provision of a machine of this character, wherein the envelopes after their filling or stuffing are ejected automatically from the machine for the sealing operation, the ejecting mechanism being of novel form and is timed for operation with the mechanism for filling or stuffing of the envelopes in a single operation of the machine.

A still further object of the invention is the provision of a machine of this character, which is comparatively simple in construction, thoroughly reliable and efficient in operation, automatic in its working, enabling the filling of the envelopes with dispatch, and inexpensive to manufacture and install.

With these and other objects in view the invention consists in the features of construction, combination and arrangement of parts as will be hereinafter more fully described in detail, illustrated in the accompanying drawings which disclose the preferred embodiment of the invention and pointed out in the claims hereunto appended.

In the accompanying drawings:—

Figure 1 is a side elevation of the machine constructed in accordance with the invention, the casing of said machine being partly broken away.

Figure 2 is a top plan view of the machine.

Figure 3 is an enlarged vertical sectional elevation thereof.

Figure 4 is a front view of the envelope magazine showing the gauges thereon.

Figure 5 is an elevation of the lever control for the envelope opener finger.

Figure 6 is a fragmentary front view thereof.

Figure 7 is a top plan view of the same.

Figure 8 is an elevation of the lever control for the folded sheet guides.

Figure 9 is a fragmentary top plan view thereof.

Figure 10 is a fragmentary front view of the ejector for the stuffed or filled envelopes.

Figure 11 is a side elevation of the lever control for the ejector.

Figure 12 is a fragmentary top plan showing the opener finger in opening position with relation to an envelope.

Figure 13 is a similar view with the folded sheet guides advanced into the envelope for the stuffing of the same.

Figure 14 is a similar view with the ejector in ejecting position with relation to the envelope.

Figure 15 is a similar view with the ejector moved to delivery position.

Similar reference characters indicate corresponding parts throughout the several views in the drawings.

Referring to the drawings in detail the machine comprises a base 10 on which is mounted a body or casing 11, which may be made from metal or any suitable material and upon the top 12 of this body or casing a slideable folded sheet carrier 13, the latter being designed to work in a suitable guideway in said top and beneath a folded sheet magazine 14, which rises vertically from the top 12 of the body or casing. The magazine 14 at its delivery mouth 15 for a folded sheet 16 carries an adjustable gauge 17 for controlling the delivery of the single folded sheet from said magazine onto the carrier 13 which is designed to slide forward and backward in its movements on the top 12 of the body or casing.

At the front of the body or casing 11 is an envelope magazine 18 to accommodate a stack of envelopes 19 therein and the uppermost one being flush with the top 12 of the casing or body 11 for the stuffing or filling of such envelope in a manner presently described.

Arranged on the base 10 within the body or casing 11 at each end thereof is a bearing 20, having supported therein a horizontal shaft 21 carrying a plurality of swinging levers 22, 23, 24 and 25, while connected with the lever 22 at its upper end by a pivot 26 is a link 27, the latter being pivoted at 28 to the depending lug 29 on the carrier 13, and through the coupling 30 this lever is operated from a crank 31 of a rotating shaft 32 suitably journaled at opposite ends of the body or casing.

The shaft 32 is fitted with a worm gear 33 meshing with a worm screw or pinion 34 formed on a counter driven shaft 35 journaled in a depending hanger 36 which is within the body or casing 11 and this shaft 35 carries a belt wheel 37 over which is trained an endless driving belt 38, the same being also trained over a driving pulley 39 mounted on the power shaft 40 of a power motor 41, which in this instance is an electric motor of any standard type constituting the power unit for the machine. This motor is controlled in any desirable manner.

The lever 23 has pivoted at 42 to its upper end a link 43 which carries a swinging terminal eye 44 having engaged therein the actuator arm 45 of a rocking frame 46 pivoted in bearings 47 on the body or casing 11 and this frame constitutes a yoke for an envelope opener finger 48 to engage in the open flap end 49 of the envelope 19 as is shown in Figures 12, 13, 14 and 15 of the drawings when the machine is in operation for fully opening said envelope for the filling or stuffing thereof as will be presently described.

On opposite sides of the envelope magazine 18 next to the casing or body 11 are bearings 50 in which are vertically disposed turning stems 51, these at their upper ends are attached folded sheet guides 52 which are adapted to swing into and out of the envelope 19 when the latter has been opened up by the opener finger 48 hereinbefore referred to. The lower ends of the stems 51 have arms 53, each through the medium of the hinged jointed connection 54 is controlled by an actuator arm 55, having the connection 56 with the upper end of the lever 24 which is operated in a manner presently described.

The envelope magazine 18 below the bottom 57 thereof and adjacent its front has arranged therewith on opposite sides bearings 58 in which is pivoted a swinging frame 59 forming a yoke for an envelope ejector 60, and one end of the yoke carries an arm 61, the latter being engaged with a hinged terminal eye 62 of an actuator link 63 which is pivoted at 64 with the upper end of the lever 25 which is operated in a manner presently described.

Within the envelope magazine 18 is an elevator 64 provided with an elevator stem 65, slidably fitted in upper and lower guides 66 and 67, respectively, these being formed on a guide frame 68 fixed to and depending from the bottom 57 of said magazine. The stem 65 is acted upon by a spring 69 which urges the same in an upward direction to position the uppermost envelope 19 within the magazine 18 in workable position. Operable upon the stem 65 is a grab jaw 70 which is pivoted at 71 to a depressible arm 72, the same being pivoted at 73 to a rocker 74 journaled at 75 on a bearing 76 within the body or casing 11. The jaw 70 is engageable with a releasing lug or screw 77 on the frame 68 and when engaged therewith frees the stem 65, but when disengaged from this lug or screw it grabs the stem under the action of a tensioning spring 78 connected with the jaw and arm 72.

The arm 72 carries a roller 79 which coacts with a cam 80 on the shaft 32 that operates to depress said arm and on downward movement the jaw 70 grabs stem 65 and lowers it therewith for the automatic lowering of the elevator 64 and this action takes place when a filled or stuffed envelope 19 is being ejected from the machine as the filled envelope is then engaged by the sheet guides 52 so that said envelope is

slipped therefrom by the ejector for the delivery of such envelope from the machine.

The shaft 32 carries a cam 81 which coacts with a roller 82 on the lever 23, so that the latter will be operated for the working of the opener finger 48 at the proper interval during the operation of the machine.

This shaft 32 also carries a cam 83 which coacts with a roller 84 on the lever 24 so that the folded sheet guides 52 will be actuated at the proper time in the working of the machine.

This shaft 32 is further provided with a cam 85 coacting with a roller 86 on the lever 25 so the ejector 60 will be actuated at the proper time in the operation of the machine.

On the envelope magazine 18 at its inner side opposite the front is arranged a sealing flap holder 87, which is designed to engage the flap 88 of the envelope 19 when being positioned for the filling or stuffing thereof.

Hinged to the front of the folded sheet magazine 14 is a spring tensioned folded sheet latch or abutment device 89, so that when folded sheet carrier 13 enters an envelope to be filled or stuffed by way of the guides 52 a folded sheet 16 is conveyed forward from folded sheet magazine 14 past the latch or abutment 89 and upon return of the carrier 13 the folded sheet is deposited upon said carrier ready for the next cycle of operations of the machine. This latch or abutment 89 prevents the advanced folded sheet 16 by the carrier 13 from following it back for another folded sheet.

The folded sheet carrier 13 serves as a bottom for the folded sheet magazine 14 when under the same and the upper surface of this carrier is provided with a highly frictional face 90 so that when the said carrier moves the lowermost folded sheet within the magazine 14 will be carried from the latter and advanced to the envelope 19 to be filled or stuffed.

The levers 22, 23, 24 and 25 are held in contact with their cams in any suitable manner, preferably through the action of tensioning springs (not shown) these being mounted in any well known way within the machine.

It is of course understood that the cams acting upon the levers are set for timing in the successive operations of the machine for the feeding of folded sheets singly to the envelopes to be filled or stuffed and the insertions of the sheets therein and the ejection of the filled or stuffed envelopes from the machine.

In Figure 12 of the drawings the opener finger 48 has entered the envelope to be stuffed or filled, while in Figure 13 the guides 52 have been introduced into said envelope 19, then in Figure 14 the envelope has been filled with the folded sheet 16 and the filled envelope is being ejected from the machine and in Figure 15 the ejector 60 has delivered the said filled or stuffed envelope from the machine for undergoing the sealing operation.

What is claimed is:

1. In a machine of the kind described, a support having a top provided with a guideway, a slidable sheet carrier in the guideway, a sheet magazine overhanging said guideway, means for singly controlling delivery of sheets from the magazine to the carrier, an envelope magazine beneath the plane of the guideway to have an uppermost envelope of a stack flush with said guideway, a plurality of swinging levers in the support and one operating the carrier, a pivoted yoke on the support and operated by another of

the levers, a forwardly inclined opener finger on the yoke to engage in and open the uppermost envelope, laterally swinging sheet guides at opposite sides of the guideway and operated by another of the levers to swing into the envelope opened by said finger for directing an oncoming sheet into said envelope, a swinging frame opposite the first-named frame, and operated by another of the levers, a rearwardly directed 10 downwardly curved envelope ejector on the last-named frame, hinged-jointed connections between the frames and guides, and the said levers, and means for actuating the levers in timed relation to each other.

2. In a machine of the kind described, a casing, a slideable sheet carrier thereon, a sheet magazine in the path of the carrier, a gauge at the sheet magazine to control delivery of single sheets to the carrier, a plurality of levers in the casing, a vertically swinging frame operated by one lever, an envelope opening finger on the frame, opposed sheet guides pivoted for lateral swinging movement into and out of an open envelope and arranged at opposite sides of the guideway to guide an oncoming sheet into said envelope, an envelope magazine next to the guideway to present an envelope to the opening finger and the guides, an envelope ejector working at the envelope magazine and operated by another of the levers, and hinged-jointed connections between the frame, guides, ejector and levers.

3. In a machine of the kind described, a slideable sheet carrier having a pocket for a single sheet, a sheet magazine in the path of the carrier, a gauge at the sheet magazine to control delivery of single sheets from the carrier, a vertically swinging means for opening an envelope, opposed laterally swinging means for entering the envelope when opened and guiding an oncoming sheet thereinto, and means for discharging the envelope when containing the sheet, the carrier and respective means being successively controlled.

4. The combination of means for opening an envelope, a sheet feeder movable toward the envelope opened by said means, and means swingingly mounted to receive opposite edges of a sheet and movable into the open envelope to 5 guide said sheet thereinto.

5. The combination of means for opening an envelope, a sheet feeder movable toward the envelope when opened, means movably mounted to receive opposite edges of a sheet and direct it 10 into the open envelope to guide said sheet thereinto, and means ejecting the envelope after receiving the sheet.

6. The combination of means for opening an envelope, a sheet feeder movable toward the envelope opened by said means, means movably mounted to receive opposite edges of a sheet and direct it into the open envelope to guide said sheet thereinto, means for ejecting the envelope 15 after receiving the sheet, and means for operating the respective means and feeder in their order. 20

7. The combination of means for opening an envelope, a sheet feeder movable toward the envelope opened by said means, means movably mounted to receive opposite edges of a sheet and guide the same into the open envelope, 25 means for ejecting the envelope when receiving the sheet, means for operating the respective means and feeder in their order, and means for 30 delivering envelopes to the opening means.

8. The combination of means for opening an envelope, a sheet feeder movable toward the envelope opened by said means, means movably mounted to receive opposite edges of a sheet and 35 guide the same into the open envelope, means for ejecting the envelope when receiving the sheet, means for operating the respective means and feeder in their order, means for delivering envelopes to the opening means, and means for 40 delivering sheets to the sheet feeder.

HORACE C. BAKER.
